UNITED STATES PATENT OFFICE.

THOMAS J. HOPKINS, OF SODA SPRINGS, IDAHO.

MILK-PAIL.

No. 856,585.

Specification of Letters Patent.

Patented June 11, 1907.

Application filed November 20, 1906. Serial No. 344,298.

To all whom it may concern:

Be it known that I, THOMAS J. HOPKINS, a citizen of the United States, residing at Soda Springs, in the county of Bannock, State of Idaho, have invented certain new and useful Improvements in Milk-Pails; and I do hereby declare the following to be a full, clear, and exact description of the invention, such as will enable others skilled in the art to 5 which it appertains to make and use the same.

This invention relates to improvements in milk pails, and its object is to provide a simple and inexpensive article of this kind which 15 will effectively prevent the contents from spilling in case the pail should be accidentally upset or tilted.

The particular improvement consists in the provision of a double valve attached to 20 the under side of the pail top, the valve members being located at right angles to each other and movable loosely in their bearings, the lower end of said valve members being sufficiently weighted to cause the same 25 to swing on their axis from their normal or open position when the pail is tilted or upset and thus automatically close the communication between the pail and its top.

With this and other objects in view, the 30 device consists in the construction, combination and arrangement of parts, all as herein-after fully described and illustrated in the accompanying drawings, in which,

Figure 1 is an elevation of a milk pail constructed in accordance with this invention. 35 Fig. 2 is a transverse vertical section therethrough. Fig. 3 is a similar section at right angles to Fig. 2. Fig. 4 is a detail view on an enlarged scale and partly in section of the 40 double valve.

Corresponding parts are designated by like reference numerals in the several views.

Referring to the drawings, the pail consists of the receptacle or body 6, and the top 45 7, said top including a vertical flange 8 extending completely around the same and having a transverse extension 9 carrying a spout 10 having a threaded cap 11, there being an opening in the transverse extension within 50 the spout for communication with the receptacle or pail proper. The cover is likewise provided with a plate 12 extending partially across the same, as shown in Fig. 3, and connected to the inner side of the flange. A 55 vertical plate 13 is likewise carried in the cover being fastened to the flange at its sides

and to the transverse extension 9 and plate 12 at its ends, as shown in Fig. 2, the joint between said vertical plate and the flange extension and first mentioned plate being 60 sufficiently tight to prevent any leaking between the various parts.

Cover 7 also carries a strainer 14 held in place upon the upper face of plate 12 by means of a hook or latch 15 connected to 65 flange 8 and movable thereon.

To the under face of plate 12 is attached a double valve 16 passing through an opening in said plate and extending downwardly into the pail. The members 17 of said valve are 70 arranged at right angles to each other, as shown in Fig. 4, and are loosely movable in their bearings in said valve. The openings in said members are so arranged that the communication between the pail top and 75 pail will be open when both members are in their vertical position. The lower ends of said members are weighted as at 18, whereby when the pail is tilted or moved from its normal position with reference to its vertical 80 axis, said valve members will have a corresponding movement independent of the pail and will automatically close the connection between the pail and its top. The opposite end of each valve member is provided with a 85 washer and thumb-piece 21 removably attached to said members to permit the same to be withdrawn for cleaning purposes, when the thumb-piece is disengaged.

The lower end of the pail top is further 90 provided with a threaded extension 19 to enable said top to be tightly fitted upon the upper edge of the pail, there being a horizontal connecting portion 22 between the flange 8 and extension 19, upon the upper face of 95 which the plate 12 rests.

It will be obvious that when the pail with its top connected thereto is in any manner accidentally tilted or upset, the loose fit of the valve members within their bearing will 100 permit the same to swing from their normal position and immediately cut off communication between the pail top and pail and thus prevent the loss of the contents of the pail, it being understood that the spout cap is of 105 course in place upon the spout during the entire milking operation.

The pail is provided with the usual handle 23.

What is claimed, is,

1. A device of the kind described comprising in combination, a pail and a pail top; and

a double valve connected to the under side of said top, the members of said valve having weighted lower ends and being loosely movable in their bearings in said valve to automatically close communication between said top and pail when the pail is moved from its normal position with reference to its vertical axis.

2. A milk pail having a top; a strainer removably carried in said top; and a double valve connected to the under side of said top, and affording a communication between said pail and top, the members of said valve being located at right angles to each other and provided with weighted lower ends, said members being loosely movable in their bearings in said valve to automatically close communication between said top and pail whenever the pail is moved from its normal position with reference to its vertical axis.

3. In a device of the kind described in combination, a pail and a pail top; a vertical flange extending entirely around said top; a plate carried by said top and partially clos-

ing the same; a strainer carried by said top above said plate; a vertical plate connected to said flange and first mentioned plate; a spout carried on said flange adjacent said vertical plate and forming an outlet from the pail; a cap for said spout; and a double valve connected to the under side of said first mentioned plate and extending downwardly into said pail to afford a communication between said top and pail, the members of said valve being located at right angles to each other and provided with weighted lower ends, said members being loosely movable in their bearings in said valve to automatically close communication between said top and pail whenever the pail is moved from its normal position with reference to its vertical axis.

In testimony whereof, I affix my signature, in presence of two witnesses.

THOMAS J. HOPKINS.
